[57] CLAIM

The ornamental design for a multiple module serial link
encryption unit or similar article, substantially as shown
and described.

DESCRIPTION

FIG. 1 is a perspective view of a multiple module serial link
encryption unit or similar article showing our new
design;

FIG. 2 is a perspective view thereof with the hinged
keypad in the open position, the keys are shown in
broken lines in FIG. 2 for illustrative purposes only;

FIG. 3 is a top view of the unit of FIG. 1; and
FIG. 4 is a side view of the unit of FIG. 1.
